FLASK FOR MAKING SAND MOLDS
FOR CASTINGSRussell J. Hines, Bay Village, Ohio, assignor to The
Hines Flask Company, Cleveland, Ohio, a corporation
of OhioFiled May 9, 1960, Ser. No. 27,834
3 Claims. (Cl. 22—110)

This invention relates in general to apparatus for making sand molds for castings, and particularly to molds that are used in foundries for making metallic castings.

In present day foundry practice, the trend is toward the use of higher pressures in ramming or forcing sand into a flask containing a pattern for the formation of a mold for casting. This use of increased pressures results in the tendency of the walls of the conventional flask to bow or deform outwardly, and in some instances to even fracture the flask walls. A bow or deformity of the flask walls results in a deformed mold which prevents proper fitting of the conventional jackets used to enclose the mold during pouring operations, which in turn usually results in defective castings. Without a proper fit of the jacket on the mold, a run-out, shifted, or swollen casting usually occurs, resulting in a high rate of scrap castings. Also in modern molding practice where a match pattern plate is utilized to form the mold cavities in the cope and drag flask sections, it is highly important that the match plate be held against movement with respect to the flask sections to obtain proper and accurate positioning of the mold cavities with respect to the mold.

The present invention contemplates the provision of coacting projection and aperture means in or on the cope and drag flask sections and on the match plate whereby automatic aligning or centering of the match plate and cope and drag flask sections is accomplished, and with such projection and aperture means coacting to resist outward deformation of the flask walls during ramming of the sand into the flask sections in the molding operation.

Accordingly an object of the invention is to provide an improved flask arrangement for the production of sand molds for castings.

Another object of the invention is to provide an improved flask arrangement for the production of sand molds for castings and embodying coacting projecting and aperture means for accurate registering of the cope and drag flask sections, and registering of a match pattern plate therewith, while also providing for improved resistance to deformation of the walls of the flask sections during ramming of the sand into the flask sections in the mold producing operation.

A still further object of the invention is to provide detachable projection and aperture means for use with a match pattern plate and associated cope and drag flask sections, for obtaining accurate registration of the flask sections and the pattern plate, and increasing the resistance to deformation of the walls of the flask sections.

A further object of the invention is to provide projection and aperture means of the latter type, which are relatively simple and economical in nature, and which may be readily embodied in new flask constructions or embodied in existing flask constructions.

Other objects and advantages of the invention will be apparent from the following description taken in conjunction with the accompanying drawings in which:

FIG. 1 is a generally diagrammatic, vertical sectional view, illustrating a flask assembly embodying the projection and aperture means of the invention, and including cope and drag flask sections and a match pattern plate, as disposed in a molding press;

FIG. 2 is an enlarged, side elevational view of one of the

2

projection members of the invention, as adapted for use in the drag section of the flask assembly;

FIG. 3 is a top plan view of the FIG. 2 illustration;

FIG. 4 is an enlarged, side elevational view of one of the combined projection and aperture members adapted for use in the match pattern plate of the flask assembly;

FIG. 5 is a top plan view of the FIG. 4 illustration;

FIG. 6 is a bottom plan view of the FIG. 4 illustration;

FIG. 7 is an enlarged side elevational view of one of the aperture members adapted for use in the cope flask section of the flask assembly;

FIG. 8 is a top plan view of the FIG. 7 illustration;

FIG. 9 is an exploded, fragmentary, vertical sectional view of the aforementioned projection and aperture means of FIGS. 2 to 8 as assembled on the drag flask section, the match plate, and the cope flask section;

FIG. 10 is a view generally similar to FIG. 9 but showing the drag flask section, the match plate and the cope flask section in assembled relationship, and with the projection and aperture means coacting with one another to maintain accurate registration of the flask assembly and increase the resistance to deformation of the walls of the flask sections;

FIG. 11 is a reduced size, generally perspective view of a drag flask section and a match pattern plate, with a preferred arrangement of the projection and aperture means disposed thereon;

FIG. 12 is a fragmentary vertical sectional view of a drag flask section and a cope flask section embodying the above mentioned projection and aperture means, and as assembled in coacting relation to facilitate the shipping of the drag and cope flask sections as a unit.

Referring now again to the drawings and in particular to FIG. 1 thereof, there is diagrammatically illustrated a conventional molding press 10 having a press head 12 and a bed plate 14.

A flask assembly A, comprising a cope flask section 16, a drag flask section 18 and an intermediate match pattern plate 20, is disposed between the press head 12 and bed plate 14. The pattern 21 is generally centrally mounted on the plate and comprises cope and drag forming portions 21a and 21b respectively on opposite sides thereof.

The flask sections 16 and 18 in the embodiment illustrated, comprise side and end walls 22 and 24, respectively, joined in the form of a rectangle to form a hollow frame open at the top and bottom thereof. The walls may be hinged together at one corner 26 (FIG. 11), and may be provided with suitable means for locking the diagonally opposite corner, as by means of lock mechanism 28. The flask sections may also be provided with any suitable means for facilitating aligning the flask sections during assembly into stacked relation, as for example the vertically spaced apertured flanges 30 on the end walls of the flask sections, which are adapted to receive a pin 32 therethrough, for aiding in vertically aligning the flask sections in the conventional well known manner. At the top and bottom of each flask section 16 and 18, the latter's walls may be provided with the conventional flange portion 34 which projects laterally outwardly in circumscribing relation about the flask enclosure.

In accordance with the invention, projection and recess means are provided on the flask sections and match pattern plate, for obtaining accurate alignment of the match plate and flask sections when in assembled relationship, and for resisting outward deformation of the walls of the flask sections during molding operations.

Referring now to FIGS. 2 through 10 inclusive, such projection and recess means, in the embodiment illustrated, comprises a dowel member 36 adapted for mounting on the upper flange portion of the drag flask section.

Such dowel member comprises a head portion 36a, an intermediate shoulder portion 36b, and a preferably threaded base portion 36c. The head portion 36a is preferably of a smaller diameter than that of the base portion 36c, and as shown in FIG. 2. The upper end of the head portion is also preferably provided with a generally pointed, axially aligned tip 38 for a purpose to be hereinafter set forth. The shoulder portion 36b may also be provided with slots 40 therein for use in threading member 36 into a complementary threaded opening 42 (FIG. 9) in flange portion 34 on the upper end of drag flask section 18. Opening 42 may be counterbored as at 44 for coaction with shoulder portion 36b on dowel member 36 when in assembled relation and as shown in FIG. 9.

A combined dowel and recess member 48 is provided for the match plate 20. Member 48 is generally similar in construction to the aforementioned member 36 for the drag flask section, and includes head portion 48a, shoulder portion 48b and base portion 48c, with the latter mentioned base portion 48c being provided with a downwardly opening recess 50 therein. Recess 50 is formed complementary to head portion 36a of dowel member 36, and is adapted to receive portion 36a therein in the assembled condition of the drag flask section and match plate. If so desired, members 36 and 48 can be formed identically, or in other words with member 36 also possessing an opening, such as recess 50, in the base portion thereof, thereby providing for interchangeability of such members, and reducing the number of parts necessary to be stocked.

Member 48 is adapted to be threaded into a threaded through opening 54 in pattern plate 20. Opening 54 may be counterbored as at 56 in a similar manner as opening 42 in the drag flask section and so formed that the top surface 58 of the shoulder portion 48b on member 48 is disposed substantially flush with the top surface 60 of the pattern plate 20 in the assembled condition of member 48 with the pattern plate.

An aperture member or bushing 62 is provided for the cope flask section 16. Such aperture member comprises a shoulder portion 62a and a threaded base section 62b. Member 62 is provided with an opening or recess 62c extending preferably completely therethrough, and as shown in FIGS. 7 and 8.

Member 62 is adapted to be threaded into a complementary opening 64 in the bottom flange of cope flask section 16, with such opening being counterbored as at 66 for receiving shoulder portion 62a of member 62 therein. A washer member 67 is preferably disposed intermediate shoulder portion 62a of member 62 and the shoulder 66 formed by the counterbore of opening 64, so that in the event that the pattern plate 20 is of a lesser thickness than the distance between the top surface 58 of shoulder portion 48b on member 48 and the bottom boundary of member 48, then the washer member 67 can be removed to permit further threaded movement of member 62 into the opening 64 in the cope flask section, and thus any extension of shoulder portion 48b above the pattern plate surface 60 can be readily received into opening 64 in the cope drag section, without causing interference between the cope flask section and the pattern plate. It will be seen therefore that the washer 67 provides for compensation for different thicknesses of the match plate, and allows the assembly to be used with a range of thicknesses of pattern plates, such as for instance from three-eighths to a half inch.

When the pattern plate 20 and flask sections are in assembled relation as shown in FIGS. 1 and 10, the head portion 36a of member 36 of drag flask section 18 is received in smooth close fitting relation in recess 50 in member 48 on the pattern plate, and the head portion 48a of member 48 is received in smooth close fitting relation in opening 62c in aperture member 62 on the cope flask section, to accurately align the flask sections and

pattern plate. The preferable arrangement is to have two of the projection and aperture means disposed on each side of the flask sections and pattern plate, and as is shown in FIG. 11 which provides an optimum arrangement for aligning the pattern plate and flask sections and resisting flask deformation; however, more of such projection and aperture assemblies could be used on each side. It will also be understood that only one of such projection and aperture means could be utilized on each side, which would accomplish the result desired, but which would not provide the degree of resistance to flask deformation that a plural arrangement provides.

With the pattern plate and flask sections in the assembled condition as shown in FIG. 10, the making of a mold is accomplished by filling the drag flask section, which is placed in open end up condition, with sand, striking the sand off with any suitable means, such as a bottom board 68 (FIG. 1), placing the bottom board 68 on the sand inside the drag flask and then jolting the mold and 15 rolling the flask sections, pattern plate and board over so that the cope flask section is up. Then the cope flask section is filled with sand, the latter being struck off as by means of the squeeze board 70 (FIG. 1), and then the squeeze board may be placed on the sand inside the 20 cope flask section of the flask assembly. The press 10 is then operated to squeeze the sand in the drag flask section 18 toward the drag portion 21b of the match plate pattern, and the sand in the cope flask section toward the cope portion 21a of the match plate pattern, and with 25 pressures for instance up to 100 pounds per square inch. Such pressures might ordinarily cause deformation of conventional flask walls, but because of the projection and aperture means provided, coacting between the pattern plate and the flask sections, the walls of the flask sections 30 are prevented from springing out, or from being fractured, which results in much more accurate molds, and considerably extends the life of the flask assembly.

In the pop-off type of flask shown in FIG. 11, when one corner is opened in the flask assembly, or in other words the corner with the lock 28 thereon is released, there is an unequalized strain placed on the respective mold section. This may distort either the cope or drag mold portion and cause a defective mold. It will be seen that with the present arrangement, upon deactivation of the corner lock, the flask section is still prevented 40 from popping open because of the coacting dowel and recess means, until disassembly of the cope and drag flask sections from the match plate is accomplished, with much less chance of distortion of the mold upon opening 45 of the flask side walls.

As aforementioned the head portions 36a and 48a of projection members 36 and 48 respectively are provided with a pointed tip 38 thereon. Such pointed tip is for the purpose of facilitating the locating of the opening 54 in the match plate and/or the opening 64 in the cope flask 50 section. The pointed tip acts in the manner of a punch or marking point and is suitable for enabling a match plate to be placed in the customary surmounting position on the drag flask section and then is tapped slightly, as by means of a hammer, to make prick points on the confronting side thereof, which indicate the axes of the respective drills for drilling the holes in the match plate, or the bushing receiving hole in the cope flask section. It will be seen therefore that means is provided in conjunction with the projection and aperture means for definitely locating or marking the proper position of the projection and aperture means on the respective match plate or cope flask section.

As illustrated in FIG. 12, the projection and aperture 70 means in the drag and cope flask sections respectively are also advantageous for use during shipping of the flask sections as a unit assembly. As shown in FIG. 12, the head portion 36a of member 36 on the drag flask section is received in the aperture 62c of aperture member 62 on the cope flask section, when the flask sections are 75

in assembled relation. This is a definite help in the shipment of assembled flask sections because if the flask assembly is bumped or dropped in shipment, it will still hold together and not come out of line, thereby preserving the symmetry of the flask sections.

In practice it has been found satisfactory to have the head portion 36a of dowel member 36 enter the aperture 50 in member 48 on the match plate, and with the head portion 48a of member 48 enter the aperture 62c in aperture member 62 on the cope flask section, approximately a quarter to five-sixteenths of an inch. It will be seen therefore that during alignment of the cope flask section on the drag flask section to provide an assembled flask arrangement as shown in FIG. 1, the guide pins 32 do most of the initial aligning of the cope flask section with respect to the assembled drag flask section and the match plate, while the projection and aperture means of the invention is effective during finalized movement of the cope flask section into surmounting engaged relation on the match plate.

The projection and recess means 36, 48 and 62 are preferably formed of steel or like wear resistant material, and may be mass produced to provide an effective, long wearing and economical arrangement for aligning cope and drag flask sections and a match plate, and for providing effective resistance to deformation of a flask assembly.

The terms and expressions which have been employed are used as terms of description and not of limitation, and there is no intention in the use of such terms and expressions of excluding any equivalents of the features shown or described, or portions thereof, but it is recognized that various modifications are possible within the scope of the invention claimed.

I claim:

1. Detachable projection and aperture means for aligning a cope flask section, a drag flask section and an intermediate match pattern plate, adapted to be disposed in stacked relation to form a flask assembly, and for increasing the resistance of the walls of the flask sections to outward deformation during molding operations, said means comprising a first detachable member adapted to be mounted in a threaded and counterbored opening on the top surface of a wall of the drag flask section, said first member comprising an externally threaded base portion having an axially aligned aperture therein opening onto the underside of said base portion and an axially aligned upwardly projecting cylindrical-like head portion and a radially extending shoulder portion disposed intermediate said head portion and said base portion, said shoulder portion being adapted to be received in the counterbored portion of the respective opening in the drag flask section, said aperture being of a transverse cross-sectional size and of a depth formed generally complementary to the transverse cross-sectional size and height of said head portion, a second detachable member substantially identical to said first member adapted to be mounted in a threaded and counterbored opening in the match plate in axially aligned relation to said first member, the shoulder portion of said second member being adapted to be received in the counterbored portion of the respective opening in the match plate, the aperture in the base portion of said second member being adapted to receive therein in relatively close fitting relation the head portion of said first member, said first and second members being interchangeable, and a third detachable member adapted for mounting in a threaded and counterbored opening on the under surface of the corresponding wall of said cope flask section and in axially aligned relation to said second member, said third member comprising an externally threaded bushing having an axial aperture therein extending downwardly and opening onto the underside of said third member and a radially extending shoulder portion disposed adjacent the bottom extremity of said bushing, the aperture in said third member being

70
75

adapted to receive therein in relatively close fitting relation the head portion of said second member, said shoulder portion of said third member being of substantially the same diameter as the diameter of the shoulder portions of said first and second members and being adapted to be received in the counterbored portion of the respective opening in the cope flask section, and a spacer member generally encircling said bushing above said shoulder portion thereof, the last mentioned member being detachable from said bushing for providing means for varying the extent of entry of said third member into its opening in the cope flask section, whereby said projection and aperture means may be used with a lesser thickness of match plate resulting in projection of the shoulder portion of said second member above the top surface of the match plate.

2. In a molding flask assembly for making sand molds including a cope flask section, a match pattern plate and a drag flask section, each of said flask sections having a plurality of generally upright walls interconnected at their respective ends to define an enclosed boundary open at the top and bottom thereof, said match pattern plate being adapted to be positioned between said cope and drag flask sections in the assembled stacked condition of the latter for molding operation, and detachable projection and aperture means disposed in a threaded opening in each of said walls and on said match plate for aligning said flask sections and match plate and for increasing the resistance to deformation of said walls during molding operations, each of said openings being counterbored adjacent an exterior end thereof, said means comprising a first detachable member mounted in a respective one of said openings on the top surface of an associated wall of the drag flask section, said first member comprising an externally threaded base portion having an axially aligned aperture therein opening onto the underside of said base portion and an axially aligned upwardly projecting cylindrical-like head portion and a radially extending shoulder portion disposed intermediate said head portion and said base portion, said shoulder portion being received in the counterbored portion of the respective opening in the drag flask section, said aperture being of a transverse cross-sectional size and of a depth formed generally complementary to the transverse cross-sectional size and height of said head portion, a second detachable member substantially identical to said first member mounted in a respective one of said openings in the match plate in axially aligned relation to said first member, the shoulder portion of said second member being received in the counterbored portion of the respective opening in the match plate, the aperture in the base portion of said second member receiving therein in relatively close fitting relation the head portion of said first member, said first and second members being interchangeable, and a third member mounted in a respective one of said openings on the under surface of said cope flask section in axially aligned relation to said second member, said third member comprising an externally threaded bushing having an axial aperture therein extending downwardly and opening onto the underside of said third member, said third member including a radially extending shoulder portion disposed adjacent the bottom extremity of said bushing, the aperture in said third member receiving in relatively close fitting relation the head portion of said second member, said shoulder portion of said third member being of substantially the same diameter as the diameter of the shoulder portions of said first and second members and being received in the counterbored portion of the respective opening in the cope flask section, and removable means disposed above and coacting with the third member's shoulder portion for providing means for varying the extent of entry of said third member into its opening in the cope flask section upon removal of said removable means, whereby said projection and aperture means may be used with a lesser thick-

ness of match plate resulting in projection of the shoulder portion of said second member above the top surface of the match plate.

3. A flask assembly in accordance with claim 2 including means on each of said shoulder portions of each of said members for facilitating the threaded insertion and removal of the respective member into and from the respective opening in the parts of the flask assembly. 5
